UNITED STATES PATENT OFFICE.

ANDRE JANER, OF FLUSHING, NEW YORK.

DISCHARGE MECHANISM FOR CONTAINERS.

Application filed February 16, 1926. Serial No. 88,520.

This invention relates to improvements in means for permitting dry and comminuted matter, as for example salt, to be poured from a container without the necessity of removing the cover of the container.

It is an object of the invention to provide a simple and reliable device for the purpose indicated which may be readily secured within the container, and which can be cheaply manufactured.

The device consists of two relatively movable members, one of which is adapted to be secured beneath the top of the container and which has an opening therein through which the comminuted matter within the container is adapted to pass for discharge therefrom when a slide which constitutes the second essential element is moved to permit said matter to pass through said opening. More particularly the device consists of a conduit or trough-like member open at one end and having an opening in its bottom; said member serving as a housing for a conduit or slide adapted to be received therein and which when in one position will uncover the bottom opening in the housing to permit the matter within the container to flow through said opening and into the slidable conduit for passage out of the container and which when in another position will close said opening against the passage of the contents of the container, it being understood that the container must be tipped on its side or substantially inverted in order that the contents may flow therefrom.

For a fuller understanding of the invention reference is made to the detailed description thereof taken in connection with the accompanying drawing forming part of this specification and wherein the preferred form of the invention is shown.

Referring to the drawing,

Fig. 1 is a vertical section taken through the pouring device the same being shown as attached below the top of a container and as being in closed position, the view being taken on line 1—1 of Fig. 2;

Fig. 2 is an elevation of the upper part of a container, the pouring device being shown in front elevation;

Fig. 3 is a bottom plan view of the pouring device showing the same in closed position;

Fig. 4 is a view similar to Fig. 3 but showing the pouring device in open position; Fig. 5 is a vertical section taken on line 5—5 of Fig. 4, this view also showing a reinforcing sheet or plate on the upper side of the container top;

Fig. 6 is a front elevation of the pouring device alone and showing the tabs or ears by means of which it is secured to the container;

Fig. 7 is a side elevation of Fig. 6 and showing the position of the pouring device when closed;

Fig. 8 is a top view of Fig. 7; and

Fig. 9 is a view similar to Fig. 8 but showing the pouring device in open position.

In the drawings, 10 indicates the top of a cardboard container, and 11 the body thereof of which may be of any suitable form, a cylindrical form being shown. An opening is provided in the side of the container immediately below the top thereof as indicated at 12, the contents of the container passing through this opening when the pouring device is in open position.

The pouring device comprises a member generally indicated at 13 and a member 26 adapted to be slidably received within said member. The member 13 has two side walls 14 extending in parallel relation from its bottom wall 15, and one end wall 16, the member being otherwise an open member, that is to say, it is open at one end and has no top, although a top could be provided if desired without departing from the spirit of the invention. For simplicity of manufacture, however, it is preferred to make the member 13 an open top member and said member will therefore for convenience of description be hereinafter referred to as a trough-like member.

The trough-like member is secured to the top of the container by means of ears 17 extending from the edges of the end and side walls thereof, said ears being bent over the top of the container after being passed therethrough as will be readily understood, and the open end of said member is positioned adjacent the opening 12 in the container. It will be understood that the top edges of the end and side walls 16 and 14, respectively, of said member 13 as well as the up-

right edges at the open end of the same will be brought into juxtaposition with the top and side wall of the container to prevent leakage of the contents of the container past said edges. In the bottom of the trough-like member is an opening 18 through which the contents of the container enter the trough for passage through the opening 12 in the side of the container when the container is inverted and if said opening is not otherwise closed.

The opening 18 in the trough-like member 13 is controlled by the slide or slidable member 26, which has an opening 19 extending therethrough. When the slide 26 is fully pulled out both openings 18 and 19 are in register to permit the contents of the container to be poured out. The slide is provided with an extension 20 having an upturned end 21. The extension projects through a slot in the end wall 16 of the trough-like member. The length of the extension is such that when the slide is fully pulled out both of said openings 18 and 19 will register as shown in Figs. 4, 5 and 9 whereupon the contents of the container may be poured out.

The slidable member 26 is of a length to extend through the wall of the container and is provided with a pull tab 22 which, when the slide is fully pushed into the trough-like member, is disposed in close proximity to the outside wall of the container as is clearly shown in Figs. 1 and 3. It will of course be understood that when the slide is fully pushed in, the openings 18 and 19 will be out of register and the opening 18 closed by the slide.

The slide is preferably made in the form of an open-ended box-like member, the same having side walls 23 extending in parallel relation from the bottom of the slide and being provided with bent-over extensions 24 which are adapted to make frictional contact with the underside of the top of the container. The bent-over extensions are preferably of a width to meet at least along that portion which will extend beyond the container when the slide is pulled out. The slide will therefore form a conduit through which the material to be poured will flow.

If desired, the top of the container may be reinforced at the place of securement of the pouring member thereof as by means of a sheet of tin 25 (see Fig. 5) disposed on the outer side of the cover, the securing ears of the pouring device passing through said plate and being bent over in the usual manner. By providing this extra reinforcing member 25 any tendency of the pouring device securing means to pull through the cardboard will be prevented.

The pouring device may be considered as consisting of two telescoped conduits, the outer of which is secured to the container,

both conduits having bottom openings adapted to register to permit the contents of the container to be poured out through the inner conduit.

What I claim is:

1. In combination with a closed container having an opening in its side, a pair of telescoped relatively slidable conduits, the outer of which is secured beneath the top of the container and the inner of which frictionally engages with the container top, both conduits having openings extending therethrough which are normally out of register but which are adapted to register when the inner conduit is withdrawn from the outer conduit a predetermined distance, said conduits forming a passage through which the contents of the container may be poured therefrom when the openings in said conduits are in register.

2. In combination, a member having a bottom wall, upstanding side walls, and an end wall, a conduit slidable within said member and having an extension projecting through the end wall, a lug on the end of the extension for limiting the withdrawal of the conduit from said member, said member and conduit having openings in their bottom walls which are adapted to register when the conduit is withdrawn from said member as far as said extension will permit.

3. In combination, a member having a bottom wall, upstanding side walls, and an end wall, a conduit slidable within said member and having an extension projecting through the end wall, a lug on the end of the extension for limiting the withdrawal of the conduit from said member, said member and conduit having openings in their bottom walls which are adapted to register when the conduit is withdrawn from said member as far as said extension will permit, said member having ears extending from the edges of its walls whereby it may be secured to a body.

4. In combination, a member having a bottom wall, upstanding side walls, and an end wall, a conduit slidable within said member and having an extension projecting through the end wall, a lug on the end of the extension for limiting the withdrawal of the conduit from said member, said member and conduit having openings in their bottom walls which are adapted to register when the conduit is withdrawn from said member as far as said extension will permit, said member having ears extending from the edges of its walls whereby it may be secured to a body, said conduit having a downwardly extending pull tab projecting below the bottom of said member in front thereof.

5. In combination a member having a bottom wall, upstanding side walls, and an end wall, and adapted to be secured to the under side of the top of a container, a conduit slid able within said member and having an ex-

65 tension projecting through the end wall, a lug on the end of the extension for limiting the withdrawal of the conduit from said member, said member and conduit having openings in their bottom walls which are adapted to register when the conduit is withdrawn from said member as far as said extension will permit, and the upper side of said conduit being frictionally engaged by the under side of the top of the container.

6. A closure and pouring spout for containers comprising the combination with a container having an apertured wall, of an extensible conduit having relatively movable portions having openings arranged to move in and out of registry, said conduit being secured against the inside of one wall of the container with one end abutting the apertured wall thereof and projecting therethrough when said conduit is extended.

7. A closure and pouring spout for containers comprising the combination with a container having an apertured wall of an extensible conduit having a closed end and an open end and comprising relatively movable portions having openings normally out of registry but movable into registry when said conduit is extended, said conduit being secured against the inside of one wall of the container with its open end abutting the apertured wall thereof to project therethrough when said conduit is extended to bring said openings into registry.

8. A closure and pouring spout for containers comprising the combination with a container having an apertured wall, of an extensible conduit having a closed end and an open end and comprising relatively movable portions having openings normally out of registry but movable into registry when said conduit is extended, said conduit being secured on the inside of one wall of the container, with its open end adjacent the apertured wall thereof, for movement parallel to said second mentioned wall outwardly through said last mentioned wall when said conduit is extended to bring said openings into registry.

9. A closure and pouring spout for containers comprising, the combination with a container, of an extensible conduit having a closed end and an open end and comprising relatively movable portions having openings normally out of registry but movable into registry when said conduit is extended, said conduit being secured on the inside of one wall of the container with its open end at the dihedral angle formed by two walls of said container.

10. The combination with a container having an apertured wall of an extensible conduit comprising inner and outer relatively slidable members, said conduit being closed at one end and open at the other, and hav-

65 ing openings arranged to register when said conduit is extended, said conduit being secured on the inside of one wall of said container in register with the aperture in the apertured wall for movement through said aperture when said conduit is extended to bring said openings into registry.

11. The combination with a container having an apertured wall of an extensible conduit comprising inner and outer relatively slidable members, said conduit being closed 75 at one end and open at the other, and having openings arranged to register when said conduit is extended, said conduit being secured against the inside of one wall of said container in register with the aperture in the apertured wall for movement parallel to the second mentioned wall outwardly through said aperture when said conduit is extended to bring said openings into registry.

12. The combination with a container having an apertured wall of an extensible conduit comprising inner and outer relatively slidable members, said conduit being closed at one end and open at the other, and having openings arranged to register when said conduit is extended, said conduit being secured in the dihedral angle formed by two walls of said container, with its open end abutting one of said walls in register with said aperture for movement therethrough when said conduit is extended to bring said openings into registry.

13. The combination with a container having an apertured wall, of a closure and pouring spout therefor comprising inner and outer relatively slidable trough members adapted to telescope one within the other, each of said members having an opening, both of which are in register when said inner member is extended, said outer member 100 being secured against the inside of one wall of a container to support said inner member for sliding movement outward through the aperture of another wall of said container when said spout is extended.

14. In combination with a container having an apertured wall, a closure and pouring spout comprising inner and outer relatively slidable trough members adapted to telescope one within the other, each of said members having an opening both of which are in register when said inner member is extended, and said outer member being secured against the inside of one wall of a container to support said inner member for sliding movement parallel to said wall outward through the aperture of another wall of said container when said spout is extended.

15. In combination with a container having an apertured wall, a closure and pouring spout comprising inner and outer relatively slidable trough members adapted to telescope one within the other, each

of said members having an opening and said openings being in register when said inner member is extended, and said outer member being secured against the inside of one wall of a container to support said inner member with its mouth normally abutting the apertured wall of said container adja-

cent the line of intersection of said walls for movement parallel to said second mentioned wall through the aperture when said spout is 10 extended.

In testimony whereof, I have hereunto set my hand this 15 day of February, 1926.

ANDRE JANER.
